CENTRIFUGAL PUMP

Paul K. Girton, Millville, Pa., assignor to Girton Manufacturing Company, Inc., Millville, Pa., a corporation of Pennsylvania

Filed Oct. 26, 1960, Ser. No. 65,195

19 Claims. (Cl. 103—97)

This invention pertains to improvements in centrifugal pumps. More specifically stated this invention relates to improvements in centrifugal pumps of the compact type provided with fixed impellers and provided with automatic feathering or automatic adjusting impellers.

This invention also pertains to sanitary improvements in the housing and in the operative elements of the improved pump, whereby to incorporate in the pump such construction and arrangement of parts as to render the improved pump easy to maintain in sanitary condition and to enable the easy and rapid assembly, disassembly, inspection and cleaning of the pump.

This invention also pertains to improvements in the arrangement for demountably supporting the sections of the housing of the improved pump, whereby to enable the easy and quick dismantling of the pump from its support and whereby to utilize the support for accurately and independently positioning the sections of the pump housing with respect to one another and with respect to the drive mechanism of the pump.

The aspect of this invention pertaining to improvements in pump housings is claimed in the copending divisional application entitled Pump Housing, filed March 7, 1961, Serial No. 94,049, now Patent No. 3,033,121.

Centrifugal pumps of the type contemplated by this invention are frequently used in the handling of readily perishable food products, necessitating the frequent disassembly, cleaning and reassembly of the pump. In food processing establishments and in similar establishments, pumps of the type contemplated by this invention are frequently shifted from one flow system to another flow system, requiring easy adjustment of the position of the discharge connection of such pumps. In such flow systems the rate of flow of the product is frequently controlled by adjustments of valves on the discharge side of the pump. In the event such adjustments are made rapidly to reduce the volume of flow of product, overloading of the pump motor frequently occurs with the resulting damage to the driving motor.

It is therefore an object of this invention to provide a relatively simple centrifugal pump including a compound impeller mechanism having both fixed impeller elements and automatically feathering or compensating impeller elements.

A further object of this invention is to provide a compound impeller mechanism for a centrifugal pump which may be readily assembled into and also disassembled as a unit from the pumping chamber and wherein the automatically compensating or feathering impelling elements may be easily assembled onto or disassembled from the fixed or rigid impeller elements without the use of tools and without the use of any movable separate parts and wherein the automatically adjustable impeller elements are locked in operative position within the pump housing from which they may not become accidentally displaced when the pump unit is assembled in operative arrangement.

A still further object of this invention is to provide an improved pump mechanism embodying the foregoing features wherein all of the surfaces of the disassembled operative parts of the improved pump may be easily inspected without the use of any tools and may be easily cleaned.

Another object of this invention is to provide an improved sectional pump housing and an improved support for adjustably supporting such pump housing wherein the

2

sections of the pump housing are independently supported and automatically centered and aligned with the impeller mechanism and wherein the sections of the improved housing are sealed one to another by an improved seal arrangement, whereby to automatically preclude the failure of such seal irrespective of the operation of the improved pump under superatmospheric pressure or under subatmospheric pressure, and wherein the rotary seal through which the drive shaft enters the pump housing through an aperture in an end face of the housing is protected during the operation of the pump from the direct action of the pressure within the housing by the overlapping arrangement between the shaft seal and the rigid portion of the fixed impeller mechanism.

Another object of this invention is to provide an improved pump having a compound impeller consisting of a rotatable rigid, fixed impelling surface, impeller element carrying automatically compensating or feathering co-acting impeller elements, which feathering-type impelling elements are automatically adjusted to maximum impelling position solely by centrifugal force and which are automatically adjusted to reduced impelling position responsive to increases in the discharge pressure or increases in the viscosity of the material being pumped.

A further object of this invention is to provide a simple and inexpensive component for releasably locking the impelling element to the drive shaft of the pump by an arrangement which may easily and quickly be assembled and disassembled and cleaned.

An improved pump embodying the various new, novel and useful features of this invention, whereby to attain the foregoing objectives, possesses the advantages of compactness, simplicity of construction, ease and rapidity of assembly and disassembly, ease of cleaning and inspection, independent support and automatic alignment and centering of the sections of the pump housing and the impeller mechanism, ready adjustable discharge connection, rupture proof housing seal and pressure protected drive shaft seal, automatic avoidance of overload of the driving motor, ready separable impeller sections which may be assembled and disassembled without the use of tools and which are locked in operative assembly by the pump housing, and automatic feathering of sections of the compound impeller element whereby the adjustable impelling elements are expanded to maximum capacity responsive to their own centrifugal force and are depressed or contracted to minimum operative position responsive to increases in viscosity or discharge pressure of the fluid being pumped.

The foregoing and other objectives, important new, novel and useful features and advantages of this invention will become more apparent and be more easily understood upon examination of the following description thereof and the accompanying drawings and appended claims. It should, however, be remembered that, without desire of limitation, the invention will be described and illustrated as the preferred embodiment of the invention in a centrifugal pump. Certain changes and variations in the invention may, upon review of this application, suggest themselves to those skilled in the pertinent arts, which changes may, however, not depart from the spirit of this invention and may come within the scope of the appended claims.

In the accompanying drawings:

FIGURE 1 is a side elevational view, partially in broken away vertical section, of the improved centrifugal pump embodying the present invention;

FIGURE 2 is a left hand or front elevational view of the improved pump as shown in FIGURE 1, partially in broken away section, showing the automatically adjustable impeller vanes in expanded operative position and also schematically illustrating a depressed position of the automatically adjustable impeller vanes;

FIGURE 3 is a plan view of the impeller subassembly;

FIGURE 4 is a side elevational view, partially in broken away vertical section, of the impeller subassembly shown in FIGURE 3;

FIGURE 5 is a plan view of one of the automatically adjustable impeller vanes;

FIGURE 6 is an enlarged vertical fragmentary view, partially in section, showing the interrelation of the edge portions of the front pump head and the rear pump head and the casing seal and the casing support frame at the locus of coaction of those elements;

FIGURE 7 is a side view of the rear head of the housing of the improved pump showing the resilient seal for the housing sections in transverse section; and

FIGURE 8 is an elevational view illustrating the arrangement for drivingly connecting and locking the hub of the improved impeller mechanism to the drive shaft.

Referring to the drawings, in which like elements are identified by like numerals, 10 represents a driving unit, such as an electrical motor, enclosed in a housing and having a central rotary power shaft 11 extending from one end thereof and mounted in suitable bearings (not shown) adapted to support the shaft 11 against radial and axial thrust. Shaft coupling 12 is coaxially and drivingly mounted on shaft 11 in telescopic arrangement and is provided with an oil guard ring 13 on its end adjacent drive 10. Coupling 12 drivingly carries a pump drive shaft 14, coaxially arranged with the motor shaft 11 for rotation by shaft 11. A cylindrical support frame or element 15, for supporting a pump housing is coaxially mounted in fixed position on the end of the driving unit 10 and surrounds the shaft 11 and the coupling 12 and the inner end of the pump shaft 14. The end of the frame or support 15 farthest removed from the motor 10 is in a plane perpendicular to the axis of pump shaft 14 and that end of the substantially cylindrical frame 15 is provided with a cylindrical inner face 16 coaxially arranged with respect to pump shaft 14. An annular flange 17 extends inwardly from face 16 and is provided with a flat face 18 perpendicular to the cylindrical face 16 and the axis of shaft 14. Face 18 together with face 16 forms an outwardly or forwardly opening right angle groove 19 having concentric annular faces 16 and 18.

A sectional pump casing or housing is supported on the free end of frame 15 and is formed of front housing section 20 which is substantially cup-shaped and generally cylindrical and is formed of a substantially flat and centrally apertured front head portion 21 and a substantially cylindrical side wall portion 22 which is perpendicular to front head portion 21. Side wall 22 is provided with a substantially tangential discharge connection 23. Side wall 22 is coaxial with frame 15 and shaft 14 and has an outer diameter slightly less than the inner diameter of face 16 of groove 19 whereby to permit the relatively snug telescoping of the free end of side wall 22 into the groove 19 in the forward end of frame 15 with the outer surface of wall 22 in centered or coaxial engagement with face 16. Front head 20 is perpendicular to the axis of pump shaft 14 and is provided with a cylindrical inlet connection 24 coaxial with shaft 14 and communicating with and defining the inner edge of the central and circular aperture 25 in front head 20. As thus supported, front housing section 20 may be rotated within frame 15 about the axis of shaft 14 so as to dispose the outlet connection 23 at any desired angle.

Rear housing section or rear pump head 26 comprises a substantially flat and circular disc having parallel front and rear side surfaces 27 and 28 respectively and having a central circular aperture 29 telescoped over and coaxial with pump shaft 14. The rear pump head 26 is supported perpendicular to pump shaft 14 and is parallel to front pump head 21 and is parallel to face 18 of groove 19. The cylindrical outer edge surface 30 of rear head 26 defines the outer edge of rear face 28 of head 26 and is coaxial with and of a diameter slightly less than the cylindrical face 16 of groove 19 into which the rear head 26 is telescopically seated inwardly of the side wall 22 of

housing section 20 with the edge surface 30 in coaxial and centering engagement with face 16 and with the outer portions of the circular rear face 28 of head 26 parallel to and in seating or abutting engagement with the complementary surface 18 of groove 19.

The circular inner or front surface 27 of rear casing head 26 is defined at its outer periphery by a cylindrical edge surface 31. The parallel and axially spaced cylindrical edge surfaces 30 and 31 are coaxial with shaft 14 and are positioned intermediate the parallel planes of the surfaces 27 and 28 of the rear head 26. Edge surface 30 is of greater diameter than edge surface 31 and the adjacent edges of surfaces 30 and 31 are joined by a circular and uniformly curved groove or seal seat 32, the inner portion of which groove 32 is defined by a re-entrant circular surface 33 which is coaxial with groove face 16 and which at its upper edge joins the surface 31 and extends generally rearwardly from surface 33 to an annular and flat surface 34 which is parallel to the rear face 28 and extends inwardly from the coaxial cylindrical surface 30 to join in the lower edge of the re-entrant surface 33.

The annular surface 34 of rear head 26 is parallel to and abuts against a complementary and parallel annular flat edge surface 35 which defines the radially outer portion of the inner end of side wall 22 of the front pump head 20. The inner end of the outer cylindrical surface 36 of side wall 22 terminates in the outer edge of surface 35. The inner edge of the annular surface 35 is joined, by an inwardly diverging or beveled and annular surface 37 concentric with surface 16, with the inner terminal end of the inner cylindrical surface 38 of side wall 22.

The front housing section 20 and the complementary and interfitting rear housing section 26 being thus concentrically and independently supported radially in groove 19 and being thus coaxially supported against axial displacement by flange 17, the outer peripheral portions of the housing sections 20 and 26 are sealed one to another by an annular and resilient seal ring 39, of circular cross section, snugly fitted in sealing engagement with and seated in the groove or seal seat 32 of the rear pump head 26. The circular radial cross section of seal ring 39 is sufficiently great that the outer surface of the seal ring 39 sealingly engages the beveled surface 37 of the end of the inner side of the side wall 22. Due to the re-entrant curvature of groove wall 33, any pressure within the pump chamber will tend to force the seal gasket 39 into a more compressed and more tightly engaging or sealing position. The thus supported and sealed pump housing sections 20 and 26 are locked in such operative position on frame 15 by a circular compression yoke 40 which surrounds the inlet connection 24 and compressively engages the outer front surface of the front housing section 20.

Yoke 40 is provided with two oppositely positioned and bifurcated peripheral lugs 41, receiving tension bolts 42 hingedly supported by hinge pins 43 on similar positioned lugs 44 formed on the outer surface of the frame 15. Compression nuts 45 threaded onto the free ends of bolts 42, when tightened into compressive engagement with lugs 41, produce a compressive biasing of yoke 40 toward frame 15, thereby locking the sections 20 and 26 of the housing in sealed and rigidly supported arrangement in groove 19 of frame 15, and coaxially arranged with pump shaft 14.

The aperture 29 in rear housing section 26 is sealed by a rotary seal comprised of an antifriction annular seal element 46 telescoped over pump shaft 14 and slidably and sealingly engaging the rear surface 28 of housing section 26. Seal element 46 is sealed to drive shaft 14 by gasket element 47 sealingly fitted into seal ring 46 and sealingly engaging the outer periphery of shaft 14. Seal ring 46 is maintained in sealing engagement by the compressed coil spring 48 telescoped over shaft 14 intermediate coupling collar 12 and seal ring 46, which two elements are compressively engaged by the opposite ends of the compressed spring 48.

The compound pump impeller subassembly 49, housed within the pump chamber formed of housing sections 29 and 26, includes an elongated, flat and substantially rectangular and centrally apertured and rigid and rotatable impeller element or blade 50, having straight and parallel side edge surface 51 and 52 and having curved ends 53 and 54. The curved ends 53 and 54 are both of the same radius and are parallel to and are spaced slightly inwardly from the inner cylindrical surface 38 of the housing side wall 22. Impeller element 50 also has parallel front and rear flat faces 55 and 56 respectively. Faces 55 and 56 of impeller element 50 are perpendicular to the side edge surfaces 51 and 52 and are also parallel to the front and rear pump housing heads 21 and 26. Impeller element or blade 50 is positioned within the pump housing so that the rear face 56 of impeller element 50 is positioned very close to the parallel front surface or face 27 of rear pump head 26, and so that the front face 55 of the impeller element 50 is positioned a substantial distance from the front pump head 21.

A central cylindrical hub 57 is permanently fixed at one end thereof in the central aperture in impeller element or blade 50, thereby dividing blade 50 into two oppositely directed rigid impeller arms. Hub 57 is coaxially telescoped over the free end of pump drive shaft 14 and extends from blade 50 coaxially into the pump inlet connection 24. A key or driving pin 58 extends through aligned apertures in hub 57 and shaft 14 to releasably lock impeller element 50 onto shaft 14 against axial motion and to drivingly connect impeller element 50 for rotation with shaft 14.

Cylindrical and parallel pivot pins 59 extend perpendicularly from face 55 of impeller element or blade 50 toward the front pump head 21 and have their respective central axis positioned on the longitudinal center line of blade 50 with the respective central axis of the pivots 59 spaced radially from the axis of shaft 14 by a distance slightly less than the inner radius of the housing inlet 24. Each pivot 59 is provided with an annular, peripheral groove 60 which is parallel to the adjacent flat forward face 55 of the rigid impeller blade 50, and is also provided with a straight, peripheral, longitudinally extending groove 61 which is parallel to the central axis of the respective pivot 59 and extends from the forward end of that respective pivot 59 rearwardly into the associated annular groove 60. Groove 61 is located in the semi-circular surface segment of pivot pin 59 farthest removed from hub 57 and is of the same radial depth as groove 60.

Each of the pivots 59 is provided with or pivotally carries an automatic feathering or automatic adjusting, rigid, impeller vane element 62 which is hingedly or pivotally mounted upon the pivot 59. In the operation of the improved pump, when operating at maximum pumping efficiency, vanes 59 have their free ends extended radially outwardly from the axis of shaft 14 and from the path of orbiting of the pivots 59. Such outward extension of the hinged impeller vanes 62 upon the rotation of impeller element 50 results from the centrifugal force developed within the respective vanes 62 whose respective center of gravity is always positioned or located laterally or to the side of a straight line extending from the axis of shaft 14 to the axis of the associated pivot 59 upon which the vane in question is pivotally mounted.

In operation, the direction of rotation of the fixed impeller blade or pivoted impeller carrying element 50, and the direction of orbiting of the hinged impeller vanes 62 carried thereby, is clockwise as viewed in FIGURES 2 and 3. Each impeller vane 62 consists of a substantially cylindrical and hollow pivot hub section 63 of substantially the same length as the associated pivot 59 and is telescoped in axial alignment over that pivot 59 with the flat forward end 64 of hub section 63 aligned with the flat forward end of the associated pivot 59. As viewed in FIGURES 2 and 3, pivot hub 63 is provided with a rigid vane element 65 which is rigidly fixed to hub

section 63 and which, under maximum effective pumping conditions, extends radially outwardly from shaft 14 and pivot 59. Each vane portion 65 is of a width substantially equal to the width of the pivot hub 63, which width is slightly less than the distance between the impeller element 50 and the adjacent surface of the front pump head 21. Each vane portion 65 is perpendicular to the face 55 of impeller element 50 and is of a length so that the outer end thereof, when the vane 62 is pivoted to its position of maximum radial extension on pivot 59, will extend substantially as close to the cylindrical surface 38 of casing wall 22 as do the ends 53 and 54 of impeller element 50. The outer end 66 of impeller vane portion 65 is straight and is parallel to the axis of shaft 14 and the forward and rear edges 67 and 68 respectively of vane portion 65 are flat and parallel one to another and parallel to the front housing section 21 and the rear housing section 26 and the impeller element 50, and edges 67 and 68 are spaced one from another a distance slightly less than the distance between the front pump head 21 and the impeller element 50.

As viewed in FIGURES 2 and 3, the hinged impeller vane elements or portions 65 are curved and extend outwardly from their respective pivots 59 and also extend rearwardly with respect to the path and direction of orbiting thereof. Each vane portion 65 is provided with a radially convex leading surface 69 parallel to a radially concave trailing surface 70 as viewed in a plane parallel to the plane of orbiting of elements 65. The convex surface 69 and the concave surface 70 are both perpendicular to the flat front face 55 of impeller and impeller carrier element 50.

To pivotally lock the hinged impeller element 62 on its pivot 59, there is provided an inwardly extending key 71 anchored in pivot hub 63. Key 71 has its inner end extending into groove 60, thus permitting the free pivoting of the hinged impeller section 62 upon pivot 59 until either of the sides 69 or 70 of vane 65 engage hub 57 to limit the pivotal motion of impeller section 62. To remove vane 62 from pivot 59, after impeller subassembly 49 has been removed it is only necessary to rotate vane 62 clockwise on pivot 59, as viewed in FIGURE 3, until key 71 is aligned with groove 61, whereupon hub 63 may be lifted from pivot 59. Such alignment of the inner end of key 71 and groove 61 is attainable, due to the particular positioning of groove 61 on pivot 59, only when the impeller vane 62 is pivoted from a position of maximum radial extension forwardly with respect to its direction of orbiting during operation until the convex surface of the vane portion 65 is relatively close to the hub 57. Due to the combined effects of the before mentioned curvature of vane portion 65 and the centrifugal force developed by impeller 62 during operation, such forward pivoting of vane portion 65 from a position of maximum extension to a position of alignment of key 71 and groove 61, could not take place. The normal hinging action of impeller 62, during operation of the pump, is in the opposite direction and such pivoting in such opposite direction cannot be sufficient to bring key 71 into alignment with groove 61.

It will be apparent that when the pump is assembled, vane 62 may not be accidentally dislodged from pivot 59 in the event of the possible alignment of key 71 and groove 61 while the pump is at rest, for the reason that the radially outer portion of hub 63 extends radially outwardly a distance greater than the inner periphery of the aperture 25 of the front housing head 21 and for the reason that the spacing of the front end of pivot 59 from front housing head 21 is substantially less than would be required to permit the removal of hub 63 from pivot 59.

To insure the readily releasable retention of drive pin 58 in driving engagement with the hub 57 and shaft 14, through which parts pin 58 extends through aligned apertures, a spring or resilient ring 72, consisting of multiple,

closely spaced, turns or coils portions, is telescoped over hub 57 and laced through a transverse aperture in one end of drive pin 58. The inner diameter of spring ring 72 is only slightly greater than the outer diameter of hub 57 and is less than the distance from the aperture in drive pin 58 to the opposite end of drive pin 58. As assembled in operative position, the spring ring 72 passes intermediate the free end of pin 58, which extends out of one side of hub 57, and the impeller element 50. As thus assembled, the inner diameter of spring ring 72 and the length of drive pin 58 are such as to preclude the movement of ring 72 outwardly of the free end of drive pin 58 in any position of adjustment of pin 58.

The improved pump may be readily disassembled by loosening nuts 45, swinging compression bolts 42 outwardly to clear lugs 41, removing yoke 49, removing front housing section 20 from frame 15, unlacing resilient spring ring 72 from driving pin 58, removing pin 58 from hub 57 and shaft 14, removing impeller subassembly 49 from shaft 14, and then removing the rear pump head 25 from frame 15. Seal 46 and spring 48 may then be removed from shaft 14. The impeller subassembly 49 may be disassembled as hereinbefore described. Assembly of the improved pump may be accomplished by the performance, in opposite order, of the described disassembly steps.

The relative dimensions, construction and arrangement of the hinged impeller vanes 62 and the dimensions and positioning of the hub 57 and pivots 59 are such as to insure that the center of gravity of the hinged impeller vanes 62 is always so positioned that upon the rotation of impeller subassembly 49 the vanes 62 will be radially extended solely by centrifugal force with respect to the position of shaft 14 and pivots 59.

In operation the leading convex impelling surface 69 of each of the rigid hinged impellers 62, and the leading or fixed impelling surface portions of the edge surfaces 51 and 52 of the rigid impeller element 50, urge the pumped fluid received from inlet 24 outwardly against the housing wall segment 22 for discharge through outlet 23. At maximum pumping efficiency the hinged impeller elements are extended substantially as shown in full lines in FIGURE 2. Any increase in discharge pressure, as may result from sudden closing of a valve in the discharge line, or increase in the viscosity of the pumped fluid, will cause a responsive proportionate collapse or rearward depression of the hinged impeller elements 62 toward a partially collapsed or depressed position such as is schematically illustrated by the dot and dash representation of hinged vane segments 65 of FIGURE 2. In the illustrated embodiment of the improved compound impeller, the fixed impelling surface portions of the surfaces 51 and 52 of the rigid impeller element 50 are equal to at least twenty-five percent of the total impelling surface of the improved pump, which total also includes the impelling surfaces of the hinged vanes 62, thereby providing an improved pump of great flexibility in operating conditions together with maximum protection against overloading the driving motor.

From the foregoing description of this invention and from the accompanying drawings, it will be apparent that this invention realizes the introductoryly enumerated objectives respecting the improved pump. It will similarly be apparent that the invention possesses the hereinbefore listed advantages and provides new, novel and useful improvements in a centrifugal pump.

Having thus described and illustrated the preferred embodiments of this invention, the invention is not to be interpreted as being restricted to the specifically illustrated and described embodiments, as set forth in the drawings and as hereinbefore described, except insofar as is necessitated by the appended claims and the disclosures of the prior art.

The invention is hereby claimed as follows:

1. A centrifugal pump, comprising, in combination,

5 housing means having spaced and parallel and substantially flat front and rear head portions and substantially cylindrical side wall means defining together a pumping chamber, a circular inlet aperture in the center of the front head portion of said housing means, a drive shaft aperture in the center of the rear head portion of said housing means, a rotatable drive shaft extending through said drive shaft aperture into said pumping chamber, seal means sealing said drive shaft aperture about said drive shaft, an elongated and substantially rectangular and rotatable and rigid impeller element carried centrally thereof by said drive shaft within said pumping chamber and having opposed rigid impeller arm means extending radially outwardly from the axis of rotation of said drive shaft and including integrally formed impelling surface means extending radially outwardly from the central portion of said impeller element and being formed on the leading edges of said impelling arm means and extending substantially axially of said cylindrical side wall means and disposed for rotation in a plane parallel to the plane of the rear head portion of said housing means, said rigid impeller element being positioned adjacent the rear head of said housing means and completely overlying said seal means, said rigid impeller arm means having a maximum radial dimension greater than the maximum dimension of said rigid impeller arm means taken perpendicular to the line of maximum radial dimension and having parallel and flat major front and rear surfaces parallel to and spaced from the front and rear head portions of said housing means, said impelling surface means being positioned intermediate and joining said flat major front and rear surfaces of said rigid impeller arm means, pivot means carried by said rigid impeller arm means intermediate said rigid impeller arm means and the head portion of said housing having the circular inlet aperture, the axis of said pivot means being parallel to the axis of said drive shaft and being spaced radially outwardly from said drive shaft a distance substantially equal to the radius of said inlet aperture, and impeller vane means pivotally supported upon said pivot means for rotation in an orbit about said drive shaft in a path parallel to and adjacent to the path of rotation of said rigid impeller arm means.

35 2. A pump comprising, in combination, impeller housing means having a front head portion thereof spaced from a rear head portion thereof and having side wall means defining together a pumping chamber, rotatable impeller drive means extending into said pumping chamber, rotatable and rigid impeller means rotatably carried by said drive means within said pumping chamber and having a central portion and having rigid impeller arm means extending outwardly from the axis of rotation of said drive means, said rigid impeller arm means having impelling surface means extending laterally outwardly from the central portion of said impeller means toward said side wall means and also extending from the adjacent head portion toward said other head portion a substantial distance as compared to the distance between the two head portions, cylindrical pivot means carried by said rigid impeller arm means, said pivot means being spaced radially outwardly from said drive means and being parallel to the axis of rotation of said drive means and extending from said rigid impeller arm means toward said front head portion of said housing means, and impeller vane means releasably pivoted to and pivotally carried by said pivot means and extensible radially outwardly intermediate said rigid impeller arm means and said front head portion of said housing means, said impeller vane means being rotatable in an orbit around the axis of rotation of said drive means and also being of such length and of such construction and arrangement that the center of gravity of said impeller vane means is at all times spaced circumferentially from a flat plane including the axis of rotation of said drive means and the axis of said pivot means, whereby when said pump is in operation said impeller vane means is radially ex-

tended upon said pivot means by centrifugal force generated in said impeller vane means.

3. A centrifugal pump, comprising, in combination, housing means having spaced front and rear head portions and side wall means defining together a pumping chamber, a circular inlet aperture in one of said head portions, rotatable drive shaft means extending into said pumping chamber and being axially aligned with said inlet aperture, a rotatable and rigid impeller element carried by said shaft means and having rigid impeller arm means extending radially outwardly from the axis of rotation of said shaft means and having impelling surface means comprised of leading edge means of said arm means and extending laterally outwardly from the central portion of said impeller element and also extending axially of said chamber intermediate said head portions a substantial distance as compared to the distance intermediate said head portions, pivot means carried by said rigid impeller arm means intermediate said rigid impeller arm means and said head portion having the circular inlet aperture, the axis of said pivot means being parallel to the axis of said drive shaft means and being spaced radially outwardly from said drive shaft means a distance substantially equal to the radius of said inlet aperture, and impeller vane means pivotally supported upon said pivot means for rotation in an orbit about said drive shaft means in a path parallel to and adjacent to the path of rotation of said rigid impeller arm means.

4. A pump, comprising, in combination, housing means, rotatable impeller drive shaft means extending into said housing means, a rotatable and rigid impeller element mounted on said drive shaft means within said housing means, said rigid impeller element having a rigid impeller arm means extending radially outwardly from said drive shaft means and having a leading fixed impelling surface means fixed with respect to said impeller arm means and extending laterally outwardly from the central portion of said impeller element and also extending axially with respect to said drive shaft means and being rotatable in a circular orbit in a path parallel to a surface of said housing means, pivot means carried by said rigid impeller arm means, said pivot means being spaced radially outwardly from said drive shaft means and parallel to said drive shaft means, and impeller vane means pivotally supported upon said pivot means for rotation in an orbit about said drive shaft means in a path parallel to and adjacent to the path of rotation of said fixed impelling surface means.

5. A pump, comprising, in combination, housing means having spaced front and rear head portions and side wall means defining together a pumping chamber, an aperture in one of said head portions, rotatable drive shaft means extending into said pumping chamber through said aperture, a rotatable and rigid impeller element positioned adjacent to and completely overlying said aperture and having rigid impeller arm means extending radially outwardly from the axis of rotation of said shaft means and having a leading impelling surface means formed on the leading edge of and fixed in position with respect to said arm means and extending laterally outwardly from the central portion of said impeller element and also extending axially with respect to said drive shaft means a substantial distance compared to the distance intermediate said head portions and being rotatable in a path parallel to a surface of said housing means, and impeller vane means carried by said impeller arm means and pivoted thereon eccentrically of said drive shaft means for rotation in an orbit about said drive shaft means in a path parallel to and adjacent to the path of rotation of said rigid impeller arm means.

6. A pump, comprising, in combination, impeller housing means defining a pumping chamber, rotatable impeller drive means extending into said pumping chamber, rotatable and rigid impeller means carried by said drive means within said pumping chamber and having a cen-

tral portion and having rigid impeller arm means extending outwardly from the axis of rotation of said drive means, said rigid impeller arm means having a leading edge comprising an impelling surface means extending axially with respect to said drive means within said chamber and extending laterally outwardly from the central portion of said impeller means and in fixed position with respect to said impeller means, and impeller vane means pivotally carried by said rigid impeller arm means and extensible radially outwardly from said drive means, said impeller vane means being rotatable in an orbit around the axis of rotation of said drive means and also being of such length and of such construction and arrangement that the center of gravity of said impeller vane means when rotating in said orbit is at all times spaced rearwardly with respect to its direction of rotation and circumferentially from a flat plane including the axis of rotation of said drive means and the axis of pivoting of said impeller vane means on said rigid impeller arm means.

7. A pump, comprising, in combination, housing means, rotatable impeller drive shaft means extending into said housing means, a rotatable and rigid impeller element mounted on said drive shaft means within said housing means, said rigid impeller element having rigid impeller arm means extending radially outwardly from said drive shaft means and said arm means having a leading edge comprising an impelling surface means extending axially with respect to said shaft means within said housing means and extending laterally outwardly from the central portion of said impeller element and rotatable in a circular orbit in a path parallel to a surface of said housing means and in fixed position with respect to said arm means, and impeller vane means carried by said rigid impeller arm means and pivoted thereon eccentrically of said drive shaft means for rotation in an orbit about said drive shaft means in a path parallel to and adjacent to the path of rotation of said impelling surface means.

8. A centrifugal pump, comprising, in combination, a pump housing of substantially cylindrical configuration and having a centrally apertured front head portion spaced from and parallel to a centrally apertured rear head portion and also having a side wall portion, said front head portion and said rear head portion being substantially flat and substantially circular, said side wall portion being substantially cylindrical and coaxial with said front head portion and with said rear head portion and forming therewith a substantially cylindrical pumping chamber, annular seal means sealingly engaging adjacent surfaces of said side wall and said rear head portion, rotatable cylindrical drive shaft means axially aligned with the apertures in said front head portion and said rear head portion and extending into said pumping chamber through the aperture in said rear head portion, circular inlet means communicating with and axially aligned with the aperture in said front head portion, seal means for sealing the space intermediate said drive shaft means and the adjacent edge of the aperture in said rear head portion, rotatable and rigid impeller means releasably carried by said drive shaft means within said pumping chamber, said impeller means having radially extending arm means provided with substantially flat and parallel front and rear face surfaces which are perpendicular to the axis of said drive shaft means and each of which faces is substantially of a configuration of an elongated rectangle having rounded ends, said impeller means also having a cylindrical central hub portion telescoped over and axially aligned with said drive shaft means and having one end of said hub portion extending through the aperture in said front head portion, said rigid impeller means being positioned adjacent to and completely overlying said aperture in said rear head portion and having leading edge means comprising impelling surfaces extending laterally outwardly from the central portion of

said rigid impeller means and positioned intermediate said face surfaces, cylindrical pivot means carried by said rigid impeller means, said pivot means being spaced radially outwardly from and parallel to said drive shaft means and extending from said rigid impeller means toward said front head portion and having the axis of said pivot means spaced from the axis of said drive shaft means a distance substantially equal to the radius of the aperture in said front head portion, and impeller vane means releasably pivoted to and carried by said pivot means and extensible radially outwardly intermediate said rigid impeller means and said front head portion, said impeller vane means being so constructed and arranged that when rotating the center of gravity thereof is spaced rearwardly with respect to its direction of rotation and circumferentially from a flat plane including the axis of pivoting thereof and the axis of rotation of said shaft means.

9. In combination, rotatable impeller drive shaft means, rigid impeller means rotatably carried by said shaft means, said impeller means including a central portion and outwardly extending and opposed and rigid impeller arm means, said rigid impeller arm means having impelling surface means extending outwardly toward the outer ends of said rigid impeller arm means, and impeller vane means pivotally carried by said rigid impeller arm means radially outwardly of said drive shaft and rotatable in an orbit around the axis of rotation of said drive shaft means and extensible radially outwardly from the axis of pivoting of said impeller vane means, said impeller vane means being so constructed and arranged that when rotating the center of gravity thereof is spaced rearwardly with respect to its direction of rotation and circumferentially from a flat plane including the axis of rotation thereof and the axis of rotation of said shaft means.

10. An impeller for a pump, comprising, in combination, a rotatable and elongated and rigid impeller element supported upon a rotary drive shaft and having rigid impeller arm means extending radially outwardly from the axis of rotation of said impeller element, the maximum dimension of said impeller arm means taken lengthwise thereof being greater than the maximum dimension of said impeller arm means taken perpendicular to the line of said maximum lengthwise dimension thereof, said impeller arm means having leading edges comprising impelling surface means extending laterally outwardly from the central portion of said impeller element and positioned rearwardly of said impelling surface means with respect to the direction of rotation of said impeller element and impeller vane means carried by said rigid impeller arm means and pivoted thereon eccentrically of said drive shaft for said impeller element.

11. An impeller for a pump, comprising, in combination, an elongated and rigid rotatable impeller element supported upon a rotary drive shaft and having rigid impeller arm means extending radially outwardly from the axis of rotation of said impeller element, said arm means having leading edge means comprising impelling surface means, and impeller vane means carried by said rigid impeller arm means and positioned rearwardly of said impelling surface means with respect to the direction of rotation of said impeller element and pivoted thereon eccentrically of said drive shaft for said impeller element.

12. In combination, a rigid impeller means supported upon a rotary drive shaft and having a central portion and having rigid impeller arm means extending outwardly from said central portion, said impeller means being adapted to be rotated about an axis of rotation extending through said central portion, fixed impelling surfaces on said rigid impeller arm means extending laterally outwardly from said central portion, and impeller vane means pivotally carried by said rigid impeller arm means on pivot means positioned radially outwardly

of said shaft and extensible radially outwardly from the axis of rotation of said impeller means upon the rotation of said impeller means, said impeller vane means being rotatable in an orbit around the axis of rotation of said impeller means and being of such construction and arrangement that the center of gravity of said impeller vane means when rotating in such orbit is at all times spaced rearwardly with respect to its direction of rotation and circumferentially from said impelling surface and from a flat plane including the axis of rotation of said impeller means and the axis of pivoting of said impeller vane means on said rigid impeller arm means.

13. In combination, a rigid blade means having a central portion and having impelling surfaces formed on the leading edges of opposed and rigid arm means extending laterally outwardly from said central portion, said blade means being adapted to be rotated about an axis of rotation of a drive shaft supporting said blade means and extending through said central portion, and impeller vane means pivotally carried by said opposed and rigid arm means upon pivot means positioned radially outwardly of said shaft, said vane means being extensible radially outwardly from the axis of rotation of said blade means, said impeller vane means being rotatable in an orbit around the axis of rotation of said blade means and being of such construction and arrangement that the center of gravity of said impeller vane means when rotating is spaced rearwardly with respect to its direction of rotation and circumferentially from said impelling surfaces and from a flat plane including the axis of rotation of said blade means and the axis of pivoting of said impeller vane means on said rigid arm means.

14. In combination, housing means, drive shaft means extending into said housing means, impeller carrier means supported within said housing means by said drive shaft means, impeller vane means pivotally carried upon said impeller carrier means by telescoped pivot means positioned eccentrically of the axis of said drive shaft means, said impeller carrier means being so positioned with respect to said housing means as to maintain said impeller vane means pivotally supported upon said telescoped pivot means, said pivot means comprising a cylindrical inner member telescoped into an outer member, one of said members having a key means engaged with a guide surface at least partially encircling the other member, said key means and said guide surface being so constructed and arranged as to lock together said inner member and said outer member for certain predetermined positions of relative rotation of said inner member with respect to said outer member and to permit axial movement of said inner member with respect to said outer member in another predetermined position of relative rotation of said inner member with respect to said outer member.

15. An impeller for a pump, comprising, in combination, a rotatable impeller element having rigid impeller arm means extending radially outwardly from the axis of rotation of said impeller element, impeller vane means carried by said rigid impeller arm means and pivoted thereon eccentrically of the axis of rotation of said impeller element, pivot means fixed to said rigid impeller arm means and pivotally carrying said impeller vane means for pivoting in a plane spaced from and parallel to and overlying the path of movement of said rigid impeller arm means, annular groove means in said pivot means, and key means carried by said impeller vane means and having an end thereof extending into said groove means for pivotally retaining said impeller vane means in pivoting position upon said pivot means.

16. An impeller according to claim 15, having longitudinal groove means extending longitudinally from one end of said pivot means into said annular groove means, said longitudinal groove means and said annular groove means being so constructed and arranged that when the end of said key means which extends into said annular groove means is aligned with said longitudinal groove

means said impeller vane means may be moved longitudinally with respect to the axis of said pivot means.

17. An impeller according to claim 16, wherein said key means is so positioned in said impeller vane means and wherein said longitudinal groove means is so positioned in said pivot means and wherein said impeller vane means is so constructed and arranged that upon the rotation of said rotatable impeller element the centrifugal force generated within said impeller vane means will pivot said impeller vane means upon said pivot means into a position wherein said key means is spaced remotely from a position of alignment with said longitudinal groove means. 10

18. In combination, rotatable carrier means, carried means pivotally carried upon said carrier means by telescoped pivot means, said telescoped pivot means pivotally carrying said carried means upon said carrier means and positioned eccentrically of the axis of rotation of said carrier means, said telescoped pivot means comprising a cylindrical inner member telescoped into an outer member, one of said members having a key means engaged with a guide surface at least partially encircling the other member, said key means and said guide surface being so constructed and arranged as to lock together said inner member and said outer member for certain predetermined positions of relative rotation of said inner member with respect to said outer member and to permit axial movement of said inner member with respect to said outer member in another predetermined position of relative rotation of said inner member with respect to said outer member. 20 25 30

19. In combination, rotatable carrier means, carried means carried by said carrier means, pivot means fixed to said carrier means and pivotally carrying said carried means upon said carrier means, annular groove means in said pivot means, and key means supported by said carried means and having an end of said key means extending into said groove means for pivotally retaining said carried means in pivoting position upon said carrier means. 5
